UNITED STATES PATENT OFFICE.

ISRAEL KRUTT, OF NEW YORK, N. Y., ASSIGNOR TO WILLIAM A. RAPPEPORT, OF NEW YORK, N. Y.

SELF-FILLER MECHANISM FOR FOUNTAIN PENS.

Application filed July 10, 1924. Serial No. 725,124.

To all whom it may concern:

Be it known that I, ISRAEL KRUTT, a citizen of the United States, and resident of New York, in the county of New York and State of New York, have invented certain new and useful Improvements in Self-Filler Mechanism for Fountain Pens, of which the following is a specification.

My invention relates to self-filler mechanism for fountain pens; that is, to mechanism carried by the fountain pen for replenishing the supply of ink contained within in the pen.

More particularly stated, my invention contemplates mechanism operated in connection with a capsule of soft rubber used for retaining the ink, the purpose of my improvement being to enable the operator to compress the capsule throughout practically the entire length thereof in order to enable the capsule to fill itself with ink by suction, my device being constructed and arranged for use with ink capsules of considerable length.

25 A further object is to provide a filler mechanism of the type indicated and which is adapted to be operated by a spring pressed button at the extreme end of the pen barrel.

30 A further and more detailed object is to provide a filler mechanism comprising a parallel moving bar, a control button at the end of the pen barrel spring pressed to hold said bar normally in its collapsed position and said button being adapted to be moved manually longitudinally out of the end of the pen barrel for thereby moving the bar to capsule compressing position.

Other objects and aims of the invention 40 more or less specific than those referred to above, will be in part obvious and in part pointed out in the course of the following description of the elements, combinations, arrangements of parts, and applications of principles constituting the invention, and the scope of protection contemplated will be indicated in the appended claims.

In the accompanying drawings, which are 50 to be taken as a part of this specification and in which I shall show merely a preferred form of embodiment of the invention:

Figure 1 is a longitudinal section taken 55 substantially through the center of a foun-

tain pen provided with my device and showing the ink capsule as fully distended.

Figure 2 is a diagram indicating the manner in which my apparatus is used in connection with the ink capsule, for compressing the latter throughout practically its entire length.

Figure 3 is a section on the line 3-3 of Figure 1, looking in the direction indicated by the arrows.

Figure 4 is a section on the line 4-4 of Figure 1, looking in the direction indicated by the arrows.

The barrel of the fountain pen appears at 5, the pen section at 6, the pen point 70 at 7 and the adjustable ink feed at 8, these parts each being of the usual or any preferred form.

The pen section 6 is provided with a threaded portion 9 of reduced diameter, 75 which fits into a mating threaded portion 10 of the barrel 5.

The ink capsule is shown at 11, and has considerable length as compared with its diameter and with the diameter of the 80 barrel.

Slidably engaging the ink capsule 11 is a follow plate or bar 12, used as herein-after described and pressing thereupon. This follow plate has approximately the 85 same length as the ink capsule.

The follow plate is made of hard rubber or sheet metal, preferably polished, and is provided with two pairs of eyes 13 and 14, formed out of small integral portions 90 of the follow plate. Connected with the eyes 13, 14, and thus journaled to the follow plate 12, are a pair of rocking links 15 and 16, these links being also connected with eyes 17 and 18 which are carried by 95 and integral with a supporting strip 19. This supporting strip is made of hard rubber or sheet metal, as the case may be, and at one of its ends extends into a recess 20 and at its other end is provision with a portion 21 formed into a tongue, as shown more particularly in Figures 1 and 4.

Fitted tightly into the barrel 5 is a collar 22, so formed as to provide a passage 23 and two other passages 24-24. The collar 22 is also provided with a slot 25, merging into the passage 23. The tongue 21 of the supporting strip 19 extends through the passage 23 and terminates in a tip 26, which is bent slightly downward and into the slot 110

25. Thus the supporting strip 19 is held firmly in position.

The follow plate 12, which is always in engagement with the ink capsule 11, is free 5 to move away from the supporting strip 19 so as to compress the ink capsule, the rocking links 15 and 16 being adapted to swing for this purpose, as may be understood by comparing Figure 2 with Figure 1.

10 The barrel 5 is at one of its ends provided with a portion 27 bent slightly inward, as indicated at the right of Figure 1. Extending through this portion is a cylindrical member 28, provided with a head or button 29 and with an enlarged bearing portion 30. A spiral compression spring 31 encircles the cylindrical member 28, and engages the portion 27 of the barrel and also the bearing portion 30 of the cylindrical member 28. The tendency of the spring 31 is to force the cylindrical member 28 to the left, so that normally the movable parts thus immediately affected occupy the positions indicated for them in Figure 1.

15 25 The cylindrical member 28 carries an eye 32. Connected with this eye is a link 33, this link also being connected with an eye 34, carried by the follow plate. Whenever the head 29 is grasped by hand and pulled 20 to the right according to Figure 1, the link 33 pulls upon the follow plate 12 so as to cause it to swing away from the supporting strip 19 and also to move slightly endwise; that is, to the right according to Figures 25 1 and 2.

30 35 Connected with the cylindrical member 28 are two guide blades 35, each of arcuate form in cross section, as indicated in Figure 3. These guide blades are rigid relatively 40 to the cylindrical member 28, and extend into the passages 24 with which the collar 22 is provided as above described, and as indicated in Figure 3. Thus the guide blades 35 serve to guide the cylindrical member 28 and hold the same properly in position, while allowing the cylindrical member a limited travel.

45 50 The operator, by grasping the head 29 and pulling upon it so as to move the cylindrical member 28 to the right as indicated in Figure 2, causes the link 33 to pull upon the follow plate 12, and thus causes the follow plate to compress the ink capsule 11, as indicated in Figure 1. Compression of 55 the ink capsule causes it to expel its contents, in the manner well known in this art. This done and the front end of the pen being submerged in free ink, the operator releases the head 29; and thereupon the various movable parts are by the tension of the spring 31 caused to resume their respective normal positions, as indicated in Figure 1. The ink capsule 11, being resilient and resuming its normal shape, becomes filled with 60 65 ink.

It will be noted that the ink capsule is compressed throughout practically all of its length, because the follow plate 12 is quite lengthy and all portions of it move as a unit in compressing the ink capsule. By 70 this arrangement the ink capsule can be easily and quickly caused to expel its contents and to take a new supply of ink. Moreover the ink capsule, when used with this arrangement, can be made of considerable length and yet able to work well. The 75 expulsion of the contents of the ink capsule, whether said contents be air or stagnant ink, or a mixture of air and ink, is in any event complete, and whenever the ink capsule is compressed and allowed to regain its original form as here contemplated, it is 80 filled completely with the new ink.

The head or button 29, and in fact the entire cylindrical member 28, may be of 85 any desired shape or form either ornamental or otherwise.

I do not limit myself to the precise mechanism shown and described, as variations may be made therein without departing 90 from my invention, the scope of which is commensurate with my claims.

Having thus described my invention, what I claim as new and desire to secure by Letters Patent is as follows:

1. In a fountain pen, comprising the usual barrel and having a collapsible elongated ink capsule therein, a follow plate for collapsing said ink capsule, a pair of links by which the follow plate is mounted to move in parallel planes during the collapsing of the ink capsule, an operating member slidably mounted in the end of the barrel having a head externally of the barrel, a link connecting said operating member with said follow plate whereby withdrawal of the operating member will move the follow plate to capsule collapsing position, the end portion of the barrel having an inturned annular flange thereon constituting a shoulder facing inwardly of the barrel, the operating member having an annular shoulder thereon facing outwardly of the barrel and in opposition to the first shoulder, and a compression spring encircling the operating member interposed between said two shoulders and serving thereby to normally hold the operating member yieldingly in its innermost position and to hold the follow plate close against the wall of the barrel and therefore out of capsule collapsing position.

2. In a fountain pen, comprising the usual barrel and having a collapsible elongated ink capsule therein, a follow plate for collapsing said ink capsule, a pair of links by which the follow plate is mounted to move in parallel planes during the collapsing of the ink capsule, an operating member slidably mounted in the end of the barrel hav-

ing a head externally of the barrel, a link connecting said operating member with said follow plate whereby withdrawal of the operating member will move the follow plate to capsule collapsing position, a supporting strip extending longitudinally of the barrel by which said links are supported, a retaining member serving to retain the supporting strip in fixed relation to the barrel and said retaining member having parts cooperating with parts of the operating member to guide the operating member.

3. In a fountain pen, comprising the usual barrel and having a collapsible elongated ink capsule therein, a follow plate for collapsing said ink capsule, a pair of links by which the follow plate is mounted to move in parallel planes during the collapsing of the ink capsule, an operating member slidably mounted in the end of the barrel having a head externally of the barrel, a link connecting said operating member with said follow plate whereby withdrawal of the operating member will move the follow plate to capsule collapsing position, a supporting strip extending longitudinally of the barrel by which said links are supported, a collar arranged within the barrel engaging said supporting strip and serving thereby to hold the supporting strip in fixed relation to the barrel, said collar being shaped to provide a guideway between itself and the barrel, and a guide extension provided upon the operating member slidably re-

ceived in said guideway to thereby serve in 35 guiding the movements of the operating member.

4. In a fountain pen, comprising the usual barrel and having a collapsible elongated ink capsule therein, a follow plate for collapsing said ink capsule, a pair of links by which the follow plate is mounted to move in parallel planes during the collapsing of the ink capsule, an operating member slidably mounted in the end of the barrel having a head externally of the barrel, a link connecting said operating member with said follow plate whereby withdrawal of the operating member will move the follow plate to capsule collapsing position, a pen section engaging within the opposite end of the barrel and being shaped to provide a recess between itself and the barrel, a supporting strip extending longitudinally of the barrel by which said links are supported, a retaining collar arranged within the barrel adjacent the first mentioned end of the barrel shaped to provide a recess between itself and the barrel, said supporting strip having its opposite ends received in said two recesses respectively whereby the supporting strip is held in fixed relation to the barrel, and said collar also having parts cooperating with parts of the operating member to guide the operating member. 65

In testimony whereof I affix my signature.

ISRAEL KRUTT.
